TESTING DEVICE ADAPTER FOR CONVENTIONAL FLASHLIGHTS

Charles Roskilly, Burbank, Calif.

Application July 2, 1942, Serial No. 449,479

1 Claim. (CL 175—183)

1

The invention relates to improvements in devices for testing electrical circuits for continuity of circuit, for voltage, and for voltage in conjunction with polarity, and the primary object of the invention is to provide simple and efficient compact devices of this character which can be readily carried about on the person, and operated from a conventional flashlight, or other source of voltage.

Other important objects and advantages of the invention will be apparent from a reading of the following description taken in connection with the appended drawing, wherein for purposes of illustration a preferred embodiment of the invention is shown.

In the drawing:

Figure 1 is a general fragmentary side elevational view showing one of the testing elements installed in the bulb socket of a conventional flashlight.

Figure 2 is an enlarged side elevational view of the said element.

Figure 3 is a longitudinal vertical sectional view taken through Figure 2.

Figure 4 is a wiring diagram showing the electrical connection of the said element.

Referring in detail to the drawing the numeral 5 generally designates the testing unit as a whole which comprises an element A, shown assembled in Figure 1 of the drawing.

The element A consists of a generally cylindrical dielectric body 6 such as "Bakelite," for instance, having a substantially axial socket 7 formed in one end which is lined by a threaded adapter socket ferrule 8 to which is connected the conductors 9 and 37. The conductor 9 is led through the side of the body 6 by a suitable insulated conduit 10, the conductor 9 being of a flexible type and terminating in a stationary sleeve 11 which mounts a sharp pointed electrode or probe 12. The conductor 37 connects with the extreme left contact 35, Figures 2 and 3, as shown at the right in Figure 4. The right end of the body 6, Figure 3, opposite the socket is axially reduced as indicated by the numeral 13 and provided on its axially outward end with a threaded metal ferrule 14 constituting a connector plug. A center contact 15 mounted on the outer end of the reduced portion 13 has a conductor 16 leading into the chamber 17 which is formed in any suitable manner between the ends of the body 6 as shown in Figure 3 of the drawing. A conductor 18 similarly passes through the reduced portion 13 into the chamber 17. The conductors 16, 41 and 18, 42 make suitable electrical

2

connection with electrical resistances and other instrumentalities encased in a suitable dielectric envelope 19 which is mounted in the chamber 17 and has projecting radially therefrom a plurality of circumferentially spaced conductors 20 which terminate in contact heads which are substantially flush with the outer surface of the intermediate part of the body 6. One way to provide the chamber 17 in the body 6, would be to continue the axial socket as far as to the rear end of the chamber 17 and close the opening by a wall plug in which the needed conductors can be imbedded. Another way would be to make said body in two symmetrical halves.

15 Other circumferentially spaced conductors 21 lead from the left hand end of the envelope 19 and pass through the adjacent portion of the body 6 to connect with other circumferentially spaced contact points which emerge at the surface of the body 6 in longitudinally spaced relationship from the first-mentioned contacts. Another control conductor 22 emerges from the envelope 19 to connect with the center contact 23 of the socket 8.

25 Revolubly mounted on the reduced portion 13 between the ferrule 14 and the enlarged diameter portion of the body 6 is a non-conductive ring or annulus 24 on which is secured as indicated by the screw, numeral 25 one end portion of an 30 upwardly bowed conductive spring 26. The flat portion which is traversed by the fastening means 25 is projected into the annulus 24 for anchoring purposes as indicated by the numeral 27. The opposite end of the upwardly bowed

35 spring 26 is sharply upwardly curved as indicated by the numeral 28 to engage with the circle of contacts which underlies this portion of the spring 26. Riveted or otherwise secured as indicated by the numeral 29 to the upwardly bowed portion of the spring 26 is the relatively rigid rod or bar 30 which extends longitudinally on opposite sides of the rivet 29 and has the left hand end thereof downturned as indicated by the numeral 30 and provided with a ball contactor terminal

40 31 which is arranged to engage the circle of contacts which is aligned therewith as shown in Figures 2 and 3 of the drawing. The annulus 24 is adapted to be rotated to selectively engage the contact fingers 28 and 31 with longitudinally 45 aligned pairs of the contacts described, to condition the element A for different types of tests.

As shown in Figure 1 of the drawing the plug 14 is adapted to be screwed into the bulb socket 32 of a conventional flashlight or attached to any 55 other suitable current source, so that the ele-

ment A will be conveniently supported with relation to the work (not shown). An electric light bulb 34 of a voltage and capacity commensurate with the source of voltage supply used is mounted in the socket 8 and the electrode 12 and the base of the flashlight are then applied to connect with the circuit to be tested. As indicated in the diagram shown in Figure 4 of the drawing the contact studs 35 and 36 are arranged in pairs in two circles to be bridged by the contact fingers 28 and 31 through the agency of the rod 30 and the upwardly bowed spring 26, when the annular 24 is rotated to the proper position. The end contact 35 is connected by the wire 37 with the conductor 9 of the probe or electrode 12 between the electrode and the light bulb 34, the connection being made on the ferrule 8.

The light bulb 34 when screwed into ferrule 8 completes an electrical circuit through its filament between ferrule 8 and contact 23. Contact 23 is connected by the wire 38 with the second contact 35, and the remaining contacts reading from left to right in Figure 4 of the drawing are all connected to the wire 38 at a point corresponding to their position in the succession, with the exception of the third contact which is connected also with the eighth contact by a wire 39 which is unconnected to the wire 38. With the exception of the first and second contacts 35 all of the contacts 35 except the sixth contact are connected to the wire 38 by resistances 40 of different capacities in accordance with the tests to be made. It is to be noted that the sixth contact 35 is connected by a plain conductor to the wire 38.

The first five contacts 36 are connected to the wires 16, 41 connected to the center contact 15 on the plug of the section A, while the remaining contacts 36 are all connected to the wires 42 and 18 which lead to the ferrule 14 of the plug.

The testing operations easily performed with the element A, with the contact fingers 28 and 31 on the correspondingly numbered positions of the contact studs 35 and 36 indicated on the diagram in Figure 4 of the drawing comprise (1) a test showing continuity of an electrical circuit, (2) polarity determination for different voltages by using different capacity light bulbs 34, (3) instrument circuit checking for such an instrument, (4) instrument circuit checking for heavy instrument circuits, (5) 2½ volt check light, (6) 6 volt check light, (7) 12 volt check light, (8) 24 volt check light, (9) 110 volt check light, (10) 3 volt Bat. supply check. The check lights indicate the presence of voltage, by becoming incandescent.

The instrument check position will safely indicate continuity of an instrument circuit when the element "A" used alone is set on any of the "instrument" positions, with the element "A" secured in socket 32 of a 3 volt flashlight 33 or on other suitable 3-volt supply. In this test the probe is connected to one end of the instrument circuit and the positive terminal of the supply voltage is applied to the contact 15, the negative terminal of the voltage supply being connected to the ferrule 14 and the remaining end of the instrument circuit.

Because of the inability of the mechanic or operator to readily discern what is going on in his electrical circuits without an aid, this tester is designed to fill that need. Its instrument testing features and simplicity of operation, along with its ruggedness makes it more adaptable to the mechanic's needs than expensive instruments which are more complicated to operate and easily burned out from improper operation. The wrong

application of voltages on the tester will only burn out the bulb which is easily replaced, and inexpensive.

The device is designed for testing purposes only, and it is not to be used for illumination purposes, or for long intervals on any of its positions, with the exception of the "Cont." position No. 1 which can be used for illumination purposes if it is desired. To use the tester, remove flashlight bulb from flashlight 33, and screw it into the tester "A"; then screw the tester in the flashlight where the bulb was removed, then turn on flashlight switch.

Following is a list of the tester's different positions and their uses:

Tester on position "Cont." with light bulb of flashlight being used in tester, gives a continuity light for testing continuity of a circuit or equipment.

Tester on position "3v Bat." with or without a light bulb in tester, gives a 3 volt source for testing equipment that uses a 3 volt supply, when a two cell flashlight is used.

Tester on position "No. 1 Inst." with light bulb of flashlight being used in tester, gives a circuit for testing instruments for continuity and sensitivity. For testing instrument circuits and instruments in a ship without pulling equipment. For locating defective parts of an instrument installation. To use this test circuit, apply the tester to the instrument leads and if wiring through ship to instrument and instrument form a continuous circuit from the point tested, instrument hand will deflect. Flash test leads first while someone watches instrument to see if hand moves in right direction. If hand goes backward, reverse tester leads.

Tester on position "No. 2 Inst." with light bulb of flashlight being used in the tester, gives a circuit the same as "No. 1 Inst." except that it will give approximately twice as much hand deflection.

Tester on position "12v. Lite." with light bulb of flashlight being used in tester, gives a 12 volt hot light for testing for voltage on circuits using 12 volts.

Tester on position "24v. Lite." with light bulb of flashlight being used in the tester, gives a 24 volt hot light for testing for voltage on circuits using 24 volts.

Tester on position "6v. Lite." with light bulb of flashlight being used in the tester gives a 6 volt hot light for checking for voltage on circuits using 6 volts in cars, trucks, tractors, etc.

Tester on position "No. 5" with light bulb of flashlight being used in the tester, gives a 2½ volt hot light for testing for voltage on circuits using 2½ volts, such as instrument light circuits, 3 volt output of transformers, warning light circuits, etc.

Tester on position "110-v. Lite." with light bulb of flashlight being used in the tester gives a 110 volt hot light for testing for voltage on circuits using 110 volts.

Tester on position "Pol." with a 12 to 16 volt light bulb in the tester, which bulb comes in the tester, and the tester screwed into a flashlight 33 gives a circuit for checking polarity of voltages being worked on up to 24 volts. With a 2½ volt light bulb in tester, it will check polarity of voltages up to 12 volts. When test prod of tester is on positive potential and flashlight case is on negative, the light bulb will burn dimmer than when test points are reversed.

Some aircraft use inverters, which as a rule, have an output voltage exceeding the rated value.

In testing circuits using supposedly 26 volt and 115 volt output of inverters, the positions are as follows:

Tester in position "24v. Lite." with a 2½ to 3 volt light bulb in the tester and the tester screwed into a flashlight 33 gives a hot light for checking for voltage on a 26 volt output of inverters, Auto-syn instrument circuits, etc.

Tester in position "110-v. Lite." with a 2½ to 3 volt light bulb in the tester and the tester screwed into a flashlight 33 gives a hot light for checking for voltage on a 115 volt output of inverters, and circuits using 115 volts for drift meter gyro, radio compass, etc.

Test prod of tester is one test lead and the metal case of the flashlight is the other test lead. Light bulb must be screwed down into the tester and the tester screwed down into the flashlight, with the flashlight switch on. Continuity lights or hot lights must be checked before using them to check circuits or equipment.

Although there is shown and described herein a preferred embodiment of the invention, it is to be definitely understood that I do not desire to limit the application of the invention thereto except as might be required by the scope of the subjoined claim.

Having described the invention, what is claimed as new is:

A testing device adapter for a conventional 30

flashlight, comprising, a dielectric body, a central chamber therein, a reduced portion at one end of said body, a recessed metal socket and a cooperating base electrode therefor at the other end of said body, a light bulb mounted in series with said base electrode and said metal socket, a conductive ferrule embracing an outward portion of said reduced portion, a rotatable member embracing an inward portion of said reduced portion, a housing in said central chamber, a plurality of resistances in said housing and connected each, at one of their ends, to one of a first set of contact studs, a test prod connected to said metal socket, conductors connecting said base electrode to the other end of said resistances, a second set of contact studs, a conductor connecting a portion of said second set of studs to said ferrule, a central electrode carried by said reduced portion and connected to the remainder of said second set of studs, a two-pronged switch fixedly secured to said rotatable member, said first and second set of studs being circumferentially spaced about said body, each in the path of travel of a prong of said switch, whereby rotation of said switch will place predetermined resistances in series with said central electrode, said light and said test prod, producing predetermined test circuits when the device is mounted in the conventional bulb socket of a flashlight.

CHARLES ROSKILLY.
